UNITED STATES PATENT OFFICE.

ANNIE M. MORRISON, OF NEW YORK, N. Y.

SUPPORTING-BAND FOR APRONS.

—SPECIFICATION forming part of Letters Patent No. 361,537, dated April 19, 1887.

Application filed November 20, 1886. Serial No. 219,499. (No model.)

To all whom it may concern:

Be it known that I, ANNIE M. MORRISON, a citizen of the United States, residing at New York, in the county of New York and State of New York, have invented new and useful Improvements in Supporting-Bands for Aprons, of which the following is a specification.

It is very desirable to provide a lady's apron which can be quickly applied to and removed from the person at will without the necessity of tying and untying strings or tapes. This has heretofore been effected by slipping a pocket along the upper edge of the apron upon a spring-band adapted to clasp the 10 waist of the person and have its ends connected by a slide; but in such no provision has been made for keeping the upper edge of the apron distended along the spring-band and to hold it against stirring or moving along 15 the length of the spring, in consequence of which the apron, when in use, becomes displaced and the upper edge thereof must be frequently drawn at its ends to distend it upon the spring to keep it in proper position, which 20 is very objectionable. This is avoided by the devices disclosed in my application, Serial No. 209,256, filed July 27, 1886, where the apron is secured to a convoluted steel spring either by hooks on the spring or by strings at 25 the ends of the apron-waistband, which are passed through slots in the ends of the spring and then tied together.

My present invention dispenses with the said hooks; and it consists in the features 30 hereinafter described, and pointed out in the claims, reference being made to the accompanying drawings, in which—

Figure 1 is a perspective view of an apron provided with my invention and showing the 35 position of the parts when not in use. Fig. 2 is a detached perspective view of the convoluted spring-band in its closed position, and Fig. 3 a detached perspective view of the apron, showing the two strings at each end of the waistband for securing it to the slotted 40 ends of the spring-band.

In order to enable those skilled in the art to make and use my invention, I will now de-

scribe the same in detail, referring to the drawings, where—

The numeral 1 indicates an apron having, as here shown, a waistband, 2, in the form of a tubular pocket, in which is inserted the convoluted steel band 3, which is preferably made of spring-steel that has been cold-rolled, 50 as such will retain its inherent elasticity, no matter how frequently it may be sprung open to encircle the waist of the person. The steel band adjacent to or at each end is provided with a longitudinal slot or opening, 4, and the waistband of the apron is provided at each end with two tapes or strings, 5, one of which, at each end of the waistband, after the insertion of the steel band, is passed through the slot or opening 4, and then tied 55 to its companion string or tape, thereby securely attaching the ends of the apron-waistband to the steel band, and holding such waistband against stirring or other movement along the length of the steel band. This attachment of the waistband to the spring not only prevents movement of the waistband along the spring, but it also maintains the waistband in a distended position, so that it can never be displaced from proper position. 60 The convolute form of the steel band brings it into a small compass when not in use, which is desirable, and it can be quickly opened out and clasped around the waist, where it will support and retain the apron without other 65 fastenings.

The invention provides simple and economical means for supporting the apron and preserving its waistband in a neat tightly-drawn shape, while the apron can be rapidly and 70 conveniently detached for washing purposes.

I do not claim herein anything that is claimed in my application filed July 27, 1886, Serial No. 209,256, and allowed October 12, 75 1886.

I am aware that a veil has been provided with a circular spring-band, as in Letters Patent No. 89,879, and such I do not claim.

Having thus described my invention, what I claim is—

1. An apron having a waistband provided at

its ends with strings or tapes, in combination with a convoluted spring-band applied to the waistband and having a slot at each end, through which the apron strings or tapes are 5 passed and tied, substantially as described.

2. An apron having a tubular waistband provided at each end with two strings or tapes, in combination with a convoluted spring-band inserted in the waistband and a slot at each 10 end, through which one of the strings at each

end of the waistband is passed and tied to its companion string or tape, substantially as described.

In testimony whereof I affix my signature in presence of two witnesses.

ANNIE M. MORRISON.
